SKIDWAY

Walter W. Williams, Bloomington, Ill.

Application December 4, 1937, Serial No. 178,050

3 Claims. (Cl. 193—38)

This invention relates to improvements in dispensing apparatus and more particularly to the construction of a cabinet for containing packaged liquids, maintaining the packages at a desired 5 temperature and dispensing them one at a time.

It is an object of this invention to construct a cabinet of this character adapted to support a plurality of bottles or cylindrical containers, such as milk bottles, so as to be delivered by gravity 10 through an outlet at the bottom intermittently opened and closed by depositing a coin to free the closure thereof.

With this and other objects in view, reference is made to the accompanying sheet of drawing 15 which illustrates a preferred form of this invention with the understanding that minor changes may be made without departing from the scope thereof.

In the drawing:

20 Figure 1 is a view of a preferred form of this invention with the cover and upper portion of the cabinet removed, illustrating parts in section and parts in plan view.

Figure 2 is a view in vertical section taken on 25 the line 2—2, Figure 1, of the cooling and dispensing portion of the cabinet.

Figure 3 is an enlarged detail view in central longitudinal vertical section of the dispensing closure.

30 Figure 4 is a view in section taken on the line 4—4 of Figure 3.

In the embodiment of this invention as illustrated, a cylindrical cabinet is preferably divided into an upper section 1 to form a refrigerated compartment containing the dispensing apparatus and a lower section 2 to form a compartment to contain any desired type of refrigerating apparatus.

40 Inasmuch as any commercial type of refrigerating apparatus may be employed and does not form a part of this invention, the refrigeration apparatus is not illustrated and the compartment provided therefor is not shown in detail, being broken away and indicated by the reference 45 numeral 2.

The refrigerated compartment 1 is provided with a spaced-apart inner side wall 3, top wall 4 and bottom wall 5 with the space between the inner and outer walls filled with insulation material 6 as is customary in refrigerated compartments. The top of the cabinet is provided with a door 7 for the insertion of the bottles or cylindrical containers 8, which door is preferably circular in form, insulated similar to the cabinet 55 walls and may be secured to form an air-tight

closure, as shown, or in any other desired manner.

It is preferable to support the cylindrical packages 8, illustrated herein as the usual milk bottles used in the commercial distribution of milk, upon two equally spaced-apart annular spiral supports 5 or ramps 9 and 10 extending from the inner wall 3 of the compartment 1, each spaced apart from the top a sufficient distance to allow a bottle to be placed thereon and each terminating one above the other within a tangential housing 11 extending from the lower portion of the cabinet.

The pitch of the spiral annular supports or ramps 9 and 10 is such that as the bottles are removed from the bottom, those thereabove will descend by gravity. It is preferable to mount the 15 annular supports or ramps 9 and 10 upon the walls 3 at a slight angle such as 5° to the horizontal and provide the inner free ends with an upturned flange 12 to engage the neck of the bottle, so that in descending, the bottles will roll 20 upon a two-point contact with the support or ramp, one point of contact being the bottom of the bottle and the other the neck of the bottle, as shown.

It is preferable to arrange cooling coils 13 and 25 14 from the refrigerating apparatus upon the under sides of supports or ramps 9 and 10 and secured thereto in any desired manner. The central cylindrical space surrounded by the annular supports or ramps 9 and 10 may be employed for 30 precooling the bottles later to be placed upon dispensing spirals and may, if desired, be separated therefrom by a cylindrical spacer 15.

The housing 11 rotatably mounts a cylindrical dispensing closure closed at each end by circular 35 plates 16 and 17 and its cylindrical walls provided with a plurality of longitudinal spaced-apart depressions forming pockets 18 of sufficient size to receive and completely contain a bottle or cylindrical package to be dispensed. In the embodiment illustrated, four of such pockets 18 are shown in Figures 2 and 4. The end plates 16 and 17 are secured upon an axial shaft 19 rotatably mounted in the sides of the housing 11 to support the dispensing closure with the bottom of 40 one pocket 18 in line with the lower annular dispensing spiral 10 when another pocket 18 is in position to receive a bottle from the upper annular dispensing spiral 9, as shown in Figure 2. The bottom of the housing 11 is formed with a front 45 wall 20 embracing the cylindrical dispensing closure and is provided with an opening 21 to register with a pocket 18 to allow a bottle contained therein to pass out of the housing. The housing 11 is provided with a rear wall 22 which is a con- 55

tinuation of the inner bottom wall 5 of the refrigerated compartment 1 to embrace the cylindrical dispensing closure to the rear of the opening 21 and is then extended in a downward curved portion 23 over which the bottle 8 discharged from the pocket 18 through the opening 21 will roll to engage a stop 24 under the front of the housing 11 and spaced apart from wall 20 to form an opening 25 through which the bottle may be easily removed.

The shaft 19 of the cylindrical dispensing closure of the housing 11 passes through the outer wall thereof and through a casing 26 carried thereby to mount an operating handle 27 upon its exterior end. The casing 26 contains any desired form of coin-controlled apparatus adapted upon the insertion of a coin in the slot 28 to free the shaft 19 to allow the handle 27 to be operated to bring the next adjacent pocket 18 in alignment with the opening 21 to dispense or discharge the bottle contained therein. Such coin-controlled apparatus is a commercial article and forms no part of this invention and therefore is not illustrated in detail.

25 When the cabinet is filled, the first bottle placed upon the lower annular dispensing spiral 10, will roll down thereon and enter a pocket 18 in the cylindrical dispensing closure, as indicated by A in Figure 2, and will act as a stop for the other bottles supported upon that spiral or ramp 10. The first bottle placed upon the upper annular dispensing spiral 9 will roll down thereon and enter this pocket 18 in position to receive it in the cylindrical dispensing closure, as indicated B in Figure 2, and the other bottles on that spiral will be supported thereon, as shown in Figure 2.

Upon the first operation of the handle 27, the bottle A will be dispensed and the cylindrical walls of the dispensing closure will hold the bottles on both spirals 9 and 10 until bottle B assumes the position of the former bottle A, allowing the next bottle in the upper spiral 9 to enter this pocket 18 and assume the position of the former bottle B. Successive operations of the handle 27 will repeat the above described movements until all of the bottles in the upper spiral 9 have been dispensed and then the bottles in this

lower spiral 10 will be allowed to enter the cylindrical dispensing closure and be dispensed.

What I claim is:

1. In an apparatus for supporting and advancing by gravity to a discharge portion thereof containers of a type having a reduced neck extending from a main body portion thereof and an enlarged head on said neck, a spiral ramp mounted on said apparatus, said ramp having a flange along the inner peripheral edge, the neck 10 of each of said containers resting on the top of said flange and the head extending from said neck engaging the side of said flange to prevent endwise displacement of said container. 5

2. In an apparatus for supporting and advancing by gravity to a discharge portion thereof containers of a type having a reduced neck extending from a main body portion thereof and an enlarged head on said neck, a spiral ramp of greater width than the combined lengths of said neck 20 and main body portion, said ramp being inclined radially outwardly and downwardly and having a flange along the inner peripheral edge, the neck of each of said containers resting on the top of said flange and the head extending 25 from said neck engaging the side of said flange to prevent endwise displacement of said container in the direction of inclination of said ramp. 15

3. In an apparatus for supporting and advancing by gravity to a discharge portion thereof containers of a type having a reduced neck extending from a main body portion thereof and an enlarged head on said neck, a spiral ramp mounted on and having one edge engaging an 30 inner wall of said apparatus, said ramp being inclined toward said inner wall and being of greater width than the combined lengths of said neck and main body portions of said containers, and a flange on the free edge of said ramp, the 35 neck of each of said containers resting on the top of said flange and the head extending from said neck engaging the side of said flange to prevent endwise displacement of said container toward said wall and to maintain a spaced relation 40 therebetween. 45
